METHOD OF MAKING A MATRIX

Orby B. Crowell, Toronto, Ontario, Canada, assignor to Viceroy Manufacturing Company Limited, Toronto, Ontario, Canada

Application August 18, 1937, Serial No. 159,655

2 Claims. (Cl. 41—25)

The invention relates to the production of printing plates by a moulding process and more particularly to an improved method and means for making the matrix from a reinforced plastic capable of being moulded in impression-receiving contact with an original printing plate, type or the like.

The principal objects of the invention are to reduce the cost and the amount of work required 10 in the moulded production of printing plates and to facilitate the formation of the printing plate mould or matrix so that accurate printing plates may be quickly and economically produced without subjecting the original plates or type set up 15 to damaging crushing pressure.

The principal features of the invention reside in the novel steps of forming the matrix by first plasticizing a suitable plastic under pressure in association with a bonding element to form a 20 reinforced base capable of receiving a moulded impression with the minimum body distortion and thereafter subjecting said reinforced base to a second plasticizing operation in pressure engagement with an original printing plate, type 25 set up, or the like to permanently set said base with the desired impression therein so that rubber printing plates may be moulded directly therefrom.

In the drawing, 30 Figure 1 is an elevational part sectional view of a platen press illustrating one form of reinforced matrix forming base receiving its initial heat and pressure treatment therein.

Figure 2 is a view similar to Figure 1 illustrating a modified form of matrix forming base under initial treatment in the platen press.

Figure 3 is a plan view partly broken away showing the initially treated plastic base removed from the press.

40 Figure 4 is a perspective view of a portion of a preheated base showing a modified form of internal reinforcement.

Figure 5 is an elevational view partly in section showing a portion of the preheated base illustrated in Figures 3 and 4 subjected to a subsequent heat and pressure treatment in a platen press in association with a metallic printing plate, type set up, or the like.

Figure 6 is an enlarged fragmentary view of 50 Figure 5 showing the matrix forming base receiving its final moulded shape.

Figure 7 is a view similar to Figure 6 showing the original metal printing plate, or type set up removed and the final rubber printing plate being formed from the matrix.

In my prior Patent 2,075,507 granted March 30th, 1937, I disclosed a method and means for the production of non-metallic printing plates and the present invention is directed to improvements therover which simplify the process without sacrificing the desired accuracy. 5

In the above referred to patent the plasticizing and moulding of the matrix material was carried out in one operation while the entire plastic body was confined against spreading and the plastic 10 was thus forced into all cavities and spaces between the press heads and a faithful moulded reproduction depended on the plastic being forced to fill all of such cavities. It frequently happened that in certain type set ups a considerable 15 body of plastic was required in order to reproduce a comparatively simple printing surface and after the moulding operation it was necessary to cut or grind away the excessive portions of the matrix. The present invention eliminates this 20 necessity by first incorporating a reinforcing element during the initial and partial stage of vulcanization, after which the partially vulcanized and reinforced sheet is subjected to final and complete vulcanization while receiving this 25 moulded impression about a printing plate or the like with the minimum displacement of the matrix material.

In Figures 1 and 2 I have illustrated a platen press having a heated base 1 and heated head 2. 30

In producing the matrix forming sheet according to Figure 1, I place a sheet 3 of suitable wire screen on the base 1 and over this I arrange a sheet 4 of unvulcanized rubber (or other suitable plastic material which may be advantageously 35 employed) and pressure and heat are applied so that as the unvulcanized sheet 4 is plasticized it will fill the various interstices in the wire screen and permanently interlock therewith and form a a consolidated reinforced product ready for use 40 in the second step of the process.

The heat and pressure is maintained only sufficiently long enough to effect the partial vulcanization of the rubber sheet 4 and the permanent bonding thereof with the wire screen and I find 45 that one-sixth to one-seventh of the normal full vulcanization is quite suitable.

In the form of the invention illustrated in Figure 2 the wire screen is incorporated between two rubber sheets 4 and 4' and vulcanization is 50 also carried out only partially as indicated in connection with the product illustrated in Figure 1.

In Figure 3 the partially vulcanized reinforced sheet is shown removed from the press after its 55

initial treatment and as I have illustrated in Figure 4, I may employ a perforated metal sheet 3' which will permanently bond with the rubber sheet or sheets during the initial partial 5 vulcanization. These sheets may be made economically in large sizes of uniform thickness and smooth surfaced and after which they may be cut into smaller sheets or plates, as indicated in the interrupted lines in Figure 3.

10 In Figures 5 and 6 the second and separate step in the method is illustrated showing the cut-out piece 5 placed in a vulcanizing press in association with a printing plate 6 or other type set up which it is desired to reproduce, which 15 printing plate or other type set up is shown with cavities 6' therethrough, and it will be noted, particularly on reference to Figure 6, that only sufficient pressure is placed on the press to imbed the raised printing surfaces a 20 slight distance into the body of the part-vulcanized mass and that only a very limited local displacement of the adjacent face of the mass is brought about and the plastic mass does not flow into the cavities 6'.

25 This relation of the elements is maintained until the vulcanization of the plastic forming body is completed after which the plate 6 or other type set up is removed. A rubber printing plate is now formed by placing a thin sheet of un- 30 vulcanized rubber 7 over the impressed surface of the matrix, the latter having been preferably first treated with a suitable parting substance and by the application of heat and pressure the rubber sheet is vulcanized to receive 35 and permanently retain the impressions of the matrix to provide an accurate printing surface. The presence of the internal interlocking reinforcing elements will, by reason of its having been first bonded and consolidated with the 40 rubber sheet during an initial step of vulcanizing, effectively retain the matrix from horizontal expansion and distortion under the heat and pressure applied to vulcanize the final sheet or printing plate, thereby obtaining the desired 45 accuracy in the final product.

50 While the present invention has been developed in connection with a matrix or rubber subjected to successive vulcanizing steps, the process may be carried out in connection with other plastics by first subjecting the same to a pre-plasticizing temperature in association with the re-

inforcing agent to first effect a definite bonding of the two elements after which the reinforced and partially treated plastic will be subjected to a final plasticizing and/or permanent setting operation in impression-receiving relation to a 5 printing plate or other type set up.

The matrix formed by the above process may also be employed in the production of stereotypes or electrotypes as will be readily appreciated by those skilled in the art, in which case the steps indicated in Figure 7 will not be required. As shown in Figure 5 or 6 no barriers are required to confine the matrix-forming body against horizontal expansion, this step, as shown in my former patented process referred to, being eliminated, since in the present case the entire matrix-forming body is not subjected to a uniform pressure throughout and the reinforcing element is easily capable of confining the matrix bodily against the very slight local expansion force 20 created.

What I claim as my invention is:

1. The method of producing a rubber matrix for printing plates which comprises first firmly 25 permanently associating uncured rubber with a foraminous reinforcing element under such conditions of heat and pressure as to eliminate internal voids and only partially vulcanize the rubber medium to substantially one-sixth full vulcanization and render the composite product substantially incapable of subsequent compression, and thereafter impressing the surface with printing characters and completing the vulcanization of the rubber before removal of the said characters. 35

2. The method of producing a rubber matrix for printing plates which comprises first firmly 40 permanently associating uncured rubber with a foraminous reinforcing element under such conditions of heat and pressure as to eliminate internal voids and only partially vulcanize the rubber medium and render the composite product substantially incapable of subsequent compression, and thereafter completing the vulcanization in a second step while maintaining printing characters embedded therein only a sufficient depth to effect local displacement of the rubber body while preventing contact of the rubber with the depressed surface areas of the printing characters. 45
